UNITED STATES PATENT OFFICE.

ISAAC NAYLOR AND HENRY B. RUGGLES, OF CHICAGO, ILLINOIS.

CONTAINER MEMBER.

1,085,091.

Specification of Letters Patent.

Patented Jan. 20, 1914.

Application filed December 26, 1912. Serial No. 738,583.

To all whom it may concern:

Be it known that we, ISAAC NAYLOR and HENRY B. RUGGLES, citizens of the United States, residing at Chicago, in the county of Cook and State of Illinois, have invented certain new and useful Improvements in Container Members, of which the following is a specification.

Our invention relates to improvements in the construction of containers such as barrels, drums and pails of cylindrical form, and boxes, cases or other receptacles of rectangular form having removable ends.

The especial object of the improvements embodied herein is to produce a closure or cover member made up of superposed layers of sheets of paper or similar product pressed and cemented together by a suitable adhesive which serves not only to unite the layers together but also as a stiffener, and bound or reinforced by rims or ribs or rims and ribs formed from a suitable pulpy substance which is molded, pressed and dried in engagement with the sheeted member.

A further object of our invention is to so unite the body sheets and the stiffening ribs or rims that they will be interlocked and effectively held against separation when subjected to strains or stresses applied either externally or internally of the container or receptacle of which said members form parts.

In the accompanying drawing, we have illustrated preferred adaptations of our invention in the following views.

Figure 1 is a perspective view of a barrel head constructed according to our invention; Fig. 2 shows a barrel head having reinforcing ribs, which form one feature of our invention; Fig. 3 is a sectional view of the head shown in Fig. 1; Figs. 4, 5 and 6, show different forms of peripheral openings in the body of the head; Fig. 7 is an enlarged sectional detail of a joint between a head and the side of the container to which the head is applied; Fig. 8 is a fragmentary enlarged sectional detail showing a convex end member for barrels or drums, embodying our improvements, and Fig. 9 is a fragmentary enlarged sectional detail showing a concavo-convex end member or barrel head.

Referring to the details of the drawing, and particularly to Figs. 1, 2 and 3, the numeral 10 represents the body portion of our improved closure, the same being preferably

constructed of a plurality of layers or sheets of paper made from any suitable materials, and cemented or glued together, in superposed relation, by an adhesive or sizing substance that will serve, when dry, to increase the rigidity of the compound sheet thus produced. This fabricated or compound sheet may be circular, oval or rectangular in outline. In or near the periphery of the fabricated sheet, we preferably provide openings as 10^a, 10^b, 10^c, and between the openings, the material not removed forms tongues 10^d. We surround the edges of the body 10, with a rim 11, which is preferably formed with a rabbet 11^a, thus providing a peripheral shoulder 11^b, adapted to engage a corresponding projection or flange on the container (not shown) to which the member is applied. This rim is formed by pressing, casting or molding into the shape desired, a mass of paper or other analogous fibrous stock in soft or pulpy condition, subjecting it to considerable pressure so that portions will be forced into the openings 10^a, or 10^b, or 10^c, and then drying either by exposure to normal or heated air, the combined structure. In thus constructing our improved closure member, it will be seen that the tongues 10^d become firmly embedded in the mass forming the rim 11, and substantial portions of the rim substance enter, and interlock with, the openings 10^a, 10^b or 10^c, as shown at 11^c.

In Fig. 2, we have shown our improved cover member reinforced by transverse intersecting ribs or bars 12 of the same material that forms the rim 11. These ribs are pressed, cast or molded at the same time the rim is formed, and may be applied to either or both sides of the body portion 10, and arranged either concentrically, radially or in any other manner designed to effectively stiffen the structure. In practice, these ribs may have integral portions or tongues as 11^c which enter suitable holes, as 10^b, in the body of the cover, when applied by pressure to the body.

In Fig. 7, we have shown a modification of our invention, in applying the cast rim, 13, to but one side of the body of the cover 10, and forming it with tongues 13^a, which enter suitable openings provided in the cover and in the adjacent side member 14, respectively, the outer ends of said tongues being headed over, as shown in Fig. 7. In this style of structure, the closure is applied

at the time of making the barrel or drum, by methods of manufacture which form no part of this application for patent.

In Fig. 8, the body portion 15 is shown convex or with a bulge, thus securing the advantages incident to such shape.

In Fig. 9, we have shown two opposed body portions 15 and 16 which are convex and concave respectively, and are united by 10 a rim 17 which is common to both. These body portions are spaced from each other as indicated and in the space a ring 18 of any suitable material is placed. This ring serves as an abutment for the inner face of 15 the rim 17 in the molding of the latter around the members 15, 16.

While we have illustrated our invention in circular form and have referred to it as a closure, it will be obvious that shape is 20 not the essence of our invention, nor is it limited to application as a closure. It may, with utility, be utilized as a unit in the making of containers of any size or shape, the several units necessary to realize a complete structure being arranged or combined in any required manner, one such method being indicated in Fig. 7.

From the construction described, it will be apparent that with sides made up of 30 series of sheets and adhesive arranged and combined as described in respect to the body portion 10, and as indicated by 14, and ends formed to fit and unite with said sides, a complete, strong and tight receptacle will 35 result without resort to nails, screws or other forms of connecting devices or means. By methods of manufacture which we have invented, and for which we have made applications for Letters Patent, we are able 40 to utilize the particular structure herein described, so that a complete container can be quickly and cheaply made up.

The materials employed in the manufacture of the body and rim portions of our 45 improved container member may be anything suitable for the purpose disclosed. We prefer to use sheets or layers of a paper-like material in forming the body of the article, and paper stock or other fibrous and 50 cementitious substances for the rim and rib portions, but wish to avail ourselves of a wide range of equivalents for such materials, as the structure or article composed of a flat or plane body reinforced by 55 pressed, cast or molded rim or ribs, is the essence of our invention.

Having thus described our invention, what we claim as new and desire to obtain by Letters Patent, is:—

60 1. A container member having a body

portion of superposed compressed layers of paper combined with a suitable adhesive and stiffening medium, and a rim portion composed of a fibrous pulpy substance adapted to be molded upon said body portion, and when dry to form a rigid reinforcement for the latter, substantially as described.

2. A container member having a body portion of superposed compressed sheets of 70 paper combined with a suitable adhesive and stiffening medium, and having reinforcing portions composed of a fibrous pulpy substance adapted to be molded upon said body portion and when dry, to form rigid 75 stiffening members.

3. A container member having a plane body portion of compressed paper with 80 openings therein, and other portions composed of a fibrous pulpy substance adapted to be molded upon said body portion and to enter said openings, and when dry, to form rigid reinforcements for said body portion.

4. A container member having a plane body portion of compressed fibrous and adhesive products having peripheral openings 85 therein, and a rim portion composed of a fibrous substance adapted to be molded upon said openings, and also adapted to form, when dry, a rigid reinforcement for said 90 body portion.

5. A container member having a body portion of united sheets of fibrous and adhesive products provided with peripheral 95 tongues, and a rim composed of a fibrous pulpy substance adapted to be molded upon said body portion and to interlock with said tongues, and to form, when dry, a rigid flange for said body portion.

6. A container member having a body in 100 sheet form, and a rim secured to said body, said rim composed of a fibrous pulpy substance adapted to be molded, when in plastic condition, upon said body portion, and to form, when dry, a rigid stiffening medium 105 for said body.

7. A container member composed of a body portion formed of superposed sheets of fibrous and adhesive products, and a rim portion of cementitious and fibrous products 110 molded upon and interlocking with said body portion.

In testimony whereof we affix our signatures in the presence of two witnesses.

ISAAC NAYLOR.
HENRY B. RUGGLES.
